UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

FEEDING MECHANISM FOR ROCK DRILLS.

Application filed June 7, 1923. Serial No. 648,838.

To all whom it may concern:

Be it known that I, FRED M. SLATER, a citizen of the United States, and a resident of Easton, county of Northampton, and 5 State of Pennsylvania, have invented a certain Feeding Mechanism for Rock Drills, of which the following is a specification accompanied by drawings.

This invention relates to rock drills, but 10 more particularly to the feeding means of a stope drill, and is in some respects an improvement upon the feeding means shown and described in the co-pending application of Harry V. Haight, Serial No. 649,083 filed 15 July 2, 1923, to which I have permission to refer.

The object of the invention is to enable 20 the packing in the feed piston to be tightly pressed against the feed cylinder, in accordance with the pressure in the cylinder, so that it always remains tight and this is accomplished in an improved and simplified manner.

Another object of the invention is to produce 25 an improved means for holding the feed piston having a self tightening packing in its extreme inward position in the feed cylinder.

Further objects of the invention will hereinafter appear, and to all of these ends the invention is shown in one of its preferred forms in the accompanying drawings, in which

Figure 1 is a side elevation partly in vertical section of a stope drill embodying the invention, which may be taken as an illustrative example.

Figure 2 is an enlarged fragmentary vertical sectional view in detail of the feed piston,

Figure 3 is a transverse section taken on the line 3-3 of Figure 2, looking in the direction of the arrows, and

Figure 4 is a detail perspective view of the split spring ring.

Referring to the drawings, the stope drill has a cylinder A to which is secured the front head B by the usual side bolts C, and in which front head the drill steel D extends for receiving the impact blows of the hammer piston. The cylinder A is separated from the feed cylinder E by the head block F, to which is secured the usual rotation handle G for manually rotating the drill steel D. Motive fluid is admitted to

the machine through the inlet H and is controlled by a throttle valve, having the handle J.

In accordance with this invention, the feed piston K comprises the cap L and main head O. The cap L is adapted to have limited longitudinal movement in the main head O and the body portion of the cap is guided in the cup shaped cavity by the walls of the head. The cap L is formed with a recess P and an integral guiding projection or tongue Q, having a slot R adjacent the end thereof. Located between the main head O and the cap L is a packing S, which may be of a long fiber braided asbestos or any other material. The packing S is adapted to be pressed tightly against the feed cylinder E by the cap L, so that the greater the pressure within the feed cylinder, the more tightly will the packing be pressed against the cylinder.

In this instance, a piston rod T is formed integral with the main head O and carries the usual rock engaging pointer U at its lower end. For limiting the movement of the cap L, a pin V is inserted in the piston rod T, and passes through the slot R in the tongue Q and a cotter pin W located in the groove X in the piston rod, prevents the pin from coming loose.

A feed cylinder bushing Y is formed with a port Z for admitting pressure fluid to the feed cylinder E. A threaded projection a on the bushing Y carries a retainer member in the form of a nut b for holding the split metallic ring c, which is adapted to enter the recess P in the cap L for frictionally holding the piston K in its extreme inward position in the feed cylinder, so that the drill may be conveniently carried without the piston rod T moving outwardly in the cylinder.

The cap L is preferably cylindrical and is adapted to slide within a bore in the cup shaped main head O. At the upper end of the cap L there is provided a flange which with the cylindrical surface of the head O and the inner surface of the cylinder E forms an annular recess of rectangular cross section for the insertion of the packing material S. As the cap L is pressed into the head O this flange squeezes the packing material S against the cylinder walls and against the cylindrical surface of the cap L.

In devices of this sort the air is apt to leak under the cap and exert pressure on its under side which tends to equalize the pressure on the upper face. This is avoided in this construction since the packing material S is adapted to be squeezed against the cylindrical surface of the cap to prevent leakage to the lower faces. A relatively great pressure is therefore assured on the upper face of the cap L for pressing the packing S.

I claim:
A fluid pressure piston, comprising a cup shaped main hollow piston head, a hollow cylindrical cap having limited longitudinal

movement in said hollow head, the body portion of said cap being guided in the head cavity by the walls of the head, said cap having a flange at its outer end, packing material in the recess formed between the said cap flange and the main head, and a guiding projection formed integral with the cap and extending inwardly from the body portion of the cap into the main piston head, and means for limiting the longitudinal movement of the guiding projection and cap relatively to the main piston head.

In testimony whereof I have signed this specification.

FRED M. SLATER.
